MACHINE FOR MARKING PRICE TAGS

Thomas G. Turner, Dayton, Ohio, assignor to The Monarch Marking System Company, Dayton, Ohio, a corporation of Ohio

Application January 14, 1941, Serial No. 374,371

1 Claim. (Cl. 101—113)

This invention relates to machines for marking price tags. More particularly, the invention relates to machines into which strips of tickets are adapted to be fed for printing upon a printing platen and subsequent delivery.

Over the long period of development of price tags, a great many types of tickets have been designed. Among these, for example, have been string tickets, tickets including wire clips, and gummed labels. The first two mentioned tags are typical of those which are formed of heavy paper and which are larger than gummed labels. A severing mechanism is required to cut these larger and heavier tickets from the strip as they are printed and delivered. Also, in some instances, a mechanism is required for setting up the clips or prongs as the tickets are printed and delivered. The gummed labels are formed of lighter paper and are adapted to be torn apart on perforated or indented lines after they are delivered from the machine in printed condition in a continuous strip. The types of mechanisms required to feed these two classes of tickets are, of course, different.

Therefore, primarily, it has been the object of the present inventor to provide a machine which includes an improved arrangement of separate guideways for the respective types of tickets and printing head wherein the tickets are delivered through the respective guideways to a common platen and under a common printing head. A further and more specific object resides in the arrangement of these guideways and the reorganization of parts, particularly the relationship of one of the guideways and the reel or spool associated therewith with the roll of labels disposed beneath the extended printing arm and the arm extending directly over and along the guideway whereby the printing head engages the platen squarely and the type impression is uniform. For this purpose, the printing arm has been extended from its pivot end around and over the reel to a position extending the type chase over the common platen. In other words, this particular guideway lies parallel with the printing arm.

Furthermore, it has been an additional object of the present inventor to provide a common operating means for the strip advancing or feeding mechanisms of the respective guideways or tracks, thus making it possible to consolidate the driving mechanism and to utilize a single driving element such as a cam.

Also, due to the clearance in the guideway for the string or wire clip type of tickets, a plurality of feeding fingers is provided, one being located forwardly and adapted to engage the last notches

in the strip; that is, the notches defining the ticket to be severed in the particular cycle of operation. The other finger is located back several tickets. Thus, a double grip is provided and the feeding pressure is divided with the result that high speeds do not mar the tickets. The cooperating engagement and pressure of these fingers insure the feed of the ticket without buckling in the clearance.

It has been a further object of the inventor to provide means for adjusting these fingers as a unit and to provide means for moving and holding the forward finger out of operative position or in a position where it will not interfere with the feeding operations of the other feed which is disposed crosswise or at right angles to the one employing the double feed finger arrangement. Obviously, it is vital that provision be made to hold the forward finger out of operative position when the finger is not being used for feeding in view of the fact that it crosses the platen and would thus damage the tickets proceeding across the platen at right angles to the feeding operation of the fingers.

It has been the further object of the present inventor to provide an improved mechanism for feeding a continuous inking ribbon across the platen whereby the feed is absolutely positive and is operated by a mechanism intermittently operated by the motion of the slide carrying the feed fingers.

A still further object has been the provision of means in the guideway for accommodating tickets of various widths, as for example three, without requiring adjustment, but simply requiring varied starting of the strips as they are threaded into the guideway.

Other objects and certain advantages of the invention will be more fully apparent from the following description of the drawings in which:

Figure 1 is a perspective view of a ticket marking machine embodying the invention.

Figure 2 is a top plan view of the machine with the printing arm and housing removed or broken away to expose the actuating mechanism for the two ticket feed carriages.

Figure 3 is a sectional view taken on line 3—3 of Figure 2 through the longitudinal ticket feed guideway.

Figure 4 is a sectional view taken on line 4—4 of Figure 2 through the lateral label feed guideway.

Figure 5 is a sectional view taken on line 5—5 of Figure 4 showing in detail the mounting of the lateral feed carriage.

Figure 6 is a sectional view taken on line 6—6

of Figure 3, showing the cam pin which is utilized to lift the forward feed finger of the longitudinal feed carriage out of operating position when the lateral label feed is being used.

Figure 7 is a fragmentary sectional view taken on line 7—7 of Figure 2, showing the inking ribbon feeding means.

Figure 8 is a fragmentary sectional view taken on line 8—8 of Figure 2, showing the mounting of the inking ribbon drum in detail.

Figure 9 is a side view of the printing head arm, showing its actuating cam and its position in relation to the label guideway and spool.

Figure 10 is an exploded view showing, in perspective, the parts which comprise the label feed guideway.

In general, the machine includes two ticket guideways, disposed at right angles to one another, for feeding either one of two general types of tickets beneath a single printing head. All types of tickets are in strip form. The strips are notched or perforated at spaced intervals with the notches defining individual tickets. One of the guideways extends longitudinally of the machine, and the strips fed through it come under the printing head from the side. The other guideway extends laterally from the back to the front of the machine so that the strips fed through it come under the head from the rear.

In general, the tickets that are fed through the longitudinal guideways are heavier and larger and carry pins, staples, or strings for fastening them to merchandise. The other type of ticket, constituting the strip fed laterally of the machine, is made of light-weight paper and usually is coated with glue on the reverse side so that it may be adhesively fastened to merchandise. The heavier type tickets are severed from the strip by a knife, as they leave the machine, while the lighter tickets are dispensed in a continuous strip. Preferably, the strips of tickets which move longitudinally of the machine are comprised of tickets joined at their side edges. These strips are provided in rolls which may be mounted on a rotatable spool at the one end of the machine. The laterally fed strips are comprised of tickets joined end to end. These tickets are also provided in rolls which may be mounted on a spool near the rear of the machine beneath the printing head arm. For simplicity, the lighter tickets, which move laterally through the machine, will be referred to as gummed labels hereafter to distinguish them from the heavier tickets which move longitudinally through the machine.

The machine is mounted on a base 6 and is housed in an appropriate casing 7. A frame 8 is provided and it includes tables or ways 9 over which the tickets and labels are fed.

Referring to Figure 1 of the drawings, it may be seen that a roll of tickets is mounted on a spool 10 which is carried on a bracket 11 fastened to the right side of the machine. The strip of tickets extends across the top of the machine into a guideway 13 in which the strip is fed to position each ticket, in turn, beneath a printing head 14. As the strip moves out of the machine, the individual printed tickets are cut from the strip by a reciprocating knife 15 at the left side of the machine.

This knife may be an ordinary shearing blade driven by appropriate operating arms from a cam (not shown).

The gummed labels are in a roll which is mounted on a spool 12 at the left side near the rear of the machine. The strip of labels moves

forwardly from the spool 12 into a guideway 16 in which they are fed under the printing head, printed, and then dispensed without being separated one from the other.

Both feeding mechanisms for the two strips of tickets are operated from a common cam, indicated at 17 (Figures 2 and 3). The cam 17 is keyed to a driven shaft 18 which is mounted appropriately in journals at the rear of the machine. A throw-out clutch is utilized between the cam 17 and the driving motor (not shown). The clutch is controlled by a counting device, shown at 19, and is tripped to start the machine by a starting button shown at 20. The counter is adapted to automatically disengage the clutch after a set number of tickets has been dispensed or the clutch may be disengaged manually by a stop button shown at 21. The clutch is adapted to stop at the same point in its revolution every time that it is disengaged, imparting a complete cycle of operation to the actuating mechanism of the machine for feeding, printing, and dispensing one ticket for each revolution. The clutch is not a part of this present invention and therefore is not described in detail here.

The feed is provided by two reciprocating carriages which are slidably mounted above their respective guideways. The ticket feed carriage is indicated at 22 and the gummed label feed carriage is indicated at 23. The cam 17 actuates the ticket feed carriage 21 through a swinging lever 24 which is pivotally journaled, as at 25 (Figure 3), to the base of the machine. A roller 26, journaled medially of the length of the lever 24, rides in a track 27 in the periphery of the cam 17. The track is formed to impart a forward and a reverse stroke to the lever 24 for each revolution of the cam. The upper end of the lever 24 is bifurcated to engage a stud 28 extending from a slide bar 29 to which the longitudinal feed carriage 22 is bolted as at 30.

The gummed label feed carriage 23 is mounted in a slot 31 in a plate 32 bolted to the frame of the machine. A bracket 33, bolted to the label feed carriage (Figure 5), carries a journal stud 34. A bracket, indicated at 35, is fastened to the frame of the machine to the right of and beneath the longitudinal feed carriage. A swinging lever 36, rotatively journaled on the bracket 35, extends to engage the stud 34 on the bracket 33 which is bolted to the gummed label carriage. The end of the swinging lever 36 near the label feed carriage is bifurcated to engage the stud 34. A third bracket, indicated at 37, moves with the longitudinal feed carriage being bolted to the slide bar 29 at 38. This third bracket extends rearwardly above the lever 36 and carries a roller 39 which depends into a slot 40 in the swinging lever. The slot 40 is at an angle to the movement of the longitudinal feed carriage so that as the longitudinal feed carriage reciprocates, a lateral reciprocating motion is imparted to the gummed label feed carriage.

It will be noted from Figure 2 that the angle of the slot 40 is such that the two carriages advance together toward the printing head and withdraw together. Therefore, with one of the carriages out of feed operation, the other carriage can feed tickets to the printing head without any other adjustments or changes of mechanism being necessary.

In Figures 3 and 6, the ticket feed carriage is

shown. As stated above, the ticket feed carriage is bolted to the slide bar 29. The slide bar reciprocates in a guide groove 44 (Figure 5) in the frame of the machine to the rear of, and parallel with, the longitudinal feed way. The present structure includes the inking mechanism with the longitudinal feed carriage. This will be discussed at a later point. Two feed fingers 45 and 46 are utilized. These fingers are disposed in a carrier housing 47 which is seated in a groove in the carriage. The feed fingers 45 and 46 are in the same longitudinal line for engagement with spaced notches of the tickets. Each finger is pivoted on a pin 48 and is urged downwardly by a spring 49 which is seated in the carrier above the pins. The carrier is longitudinally adjustable with relation to the carriage to provide accurate alignment of the tickets with relation to the printing head. The carrier is held in position by a bolt 50 extending downwardly through a slot in the top of the carriage. The bolt is threaded into the carrier and extends upwardly through the slot beyond the top of the carriage. A spring 52 between a washer on the top of the carriage and the head of the bolt 50 holds the carrier up against the under side of the top of the carriage. An adjusting screw 53, threaded into the left end of the carriage, carries a large flat head 54. The head 54 engages a cross groove 55 in the left end of the carrier which extends beyond the end of the carriage. Turning the screw thus adjusts the carrier and, consequently, the feed fingers in relation to the carriage.

It will be noted from Figure 3 that the front finger of the longitudinal feed assembly would extend over the printing platen, indicated at 56, when in its left position, and would interfere with the laterally moving strip of labels. Therefore, a cam pin 57 (Figure 6) is provided to lift the forward finger when the label feed is being used. The cam pin is journaled in the forward side of the longitudinal feed carriage and extends outwardly beyond it to carry a knurled handle 58. The pin 57 is held in position by a forked bracket 60 which engages a groove in the pin. The cam pin extends into the feed finger carrier through a slot 61 and engages the top of an extension 62 of the finger. The cam is adapted to lift the front end of the finger when given a quarter of a turn. A detent, 63, comprised of a flat spring which engages a flattened face of the pin beneath the handle, is provided to hold the cam pin in one of its two positions. In the other position, the spring is under greater tension against the round side of the pin and holds it by friction. Also, in this second position, a stud 64 extending from the frame of the inking mechanism, abuts the cam and limits its throw.

The longitudinal ticket guideway is adaptable for various widths of tickets. As shown in Figures 1 and 2, the strip of tickets comes into the guideway from the right and is fed through the guideway to the left. An inner ticket guide 65 overhangs the inner edge of the strip. The outer guide 66 is adjustable for different widths of tickets. This longitudinal guideway is described in detail in a copending application of the present inventor under Serial No. 342,118, filed June 24, 1940, in which a ticket delivery mechanism and means for setting up the pins of tickets of the type having pins attached thereto, is disclosed and claimed.

As stated above, the inking mechanism is carried on the longitudinal feed carriage. The in-

king mechanism comprises an endless ink impregnated ribbon 67 which is looped over a roller 68 at the one end, and around a drum 69 at the other end. The roller 68 is carried on a removable bracket 70 which is clamped to the top of the longitudinal feed carriage by a swinging clamp arm 71 pivotally journaled on top of the carriage. A knurled knob is fixed on the top of the bracket 70 to facilitate changing of the ribbon. A table 72, made integrally with the feed carriage, extends to the left and forwardly from the feed carriage to support the inking pad. A guide roller 73 for the ribbon, journaled on a bracket 73a secured to the rear end of the table 72 near the inking pad, is provided to guide the double thickness of the looped ribbon across the face of the pad. Pairs of tangs are struck up from the corners of the pad to sustain the ribbon against lateral displacement.

The forwardly extended end of the table 72 supports a vertically disposed bracket 74 which is fastened thereon by bolts which pass through a horizontally disposed flange 75. Near the end of the bracket 74, a shaft 76 extends to the left at right angles to the bracket to support the drum 69.

The drum is rotatively journaled on the shaft 76 on a bushing 77 which is press fitted into an axial bore in the drum. The bushing carries a ratchet wheel 78 at its right end between the drum and the vertical bracket. Between the ratchet wheel 78 and the bracket, a spring washer 79 is seated against a fiber washer which abuts the bracket around the shaft 76. The spring washer provides enough friction to hold the drum against free rotation by urging the drum outwardly against the head of a bolt 80 threaded into the extended end of the shaft 76. A bell crank 81, loosely journaled on the bushing 77 between the ratchet wheel and the drum, carries a roller 82 extending at right angles to its inwardly extended arm. The other arm is urged downwardly by a spring 83. The roller is therefore under spring tension for taking up slack in the ribbon.

A cover plate, pivoted on the bracket 74, may be provided to protect the operator from the inked ribbon. The cover is pivoted to swing outwardly for facilitating ribbon inspections and replacement.

The longitudinal movement of the ticket feed carriage actuates the drum. This is accomplished by a reciprocating arm 84 which rides in a channel 85 in the table parallel to the ribbon. The arm 84 is enclosed in the channel 85 by a cover plate 86 bolted to the table. A roller 86a extends through a slot in the bottom of the channel 85 to depend below the table. The roller is engageable in an angular slot 87a in the horizontal face of a plate 88a which is bolted to the top of the machine. Therefore, when the inking mechanism is driven to reciprocate longitudinally, the arm 84 is driven to reciprocate laterally. A pawl 87, carried on the outer end of the arm 84, engages the ratchet wheel 78 and thus drives the drum to rotate the ribbon. The pawl is pivotally mounted in a slot in the end of the arm 84 and is provided with a spring to urge the end of the pawl into engagement with the ratchet teeth on the forward movement and slip over them on the return movement of the arm.

The laterally reciprocating label feed carriage, as stated above, is slidably mounted in the slot 31 in the vertical plate 32. The label feed carriage (Figure 4) includes a feed finger carrier

88 which is carried on an angle bracket 89. The bracket 89 is mounted in a channel plate 90 and held therein by a bolt 91 which passes through a slot in the bracket 89 and threads into the channel plate 90. The slot provides adjustment of the feed finger carrier so that the finger can be adjusted in relation to the printing head to correctly position the labels beneath it. The channel plate 90 abuts the left side of the plate 32 and is wider than the slot 31. A slide bar 92, slidable in the slot 32, is fixed to the channel plate 90 by bolts which thread through the label feed carriage bracket 33, the slide bar 92, and into the channel plate. The carriage bracket 33 is also wider than the slot so that the carriage assembly is held against displacement from the slot.

A feed finger 93, pivotally mounted in the carrier 88, is urged downwardly at its forward end by a spring seated in the carrier above the finger. A rear extension of the finger is adapted to be depressed, thus lifting the forward end of the finger, for threading the labels into feeding position in the guideway, by a cam pin 94 which is journalled in the angle bracket 89, at the one end, and in a bracket 95 bolted to the carriage 88, at the other end.

The cam pin has a flattened portion at 96 which rests on the top of the extension of the finger 93. Thus, when the cam pin is given a quarter turn, the front of the finger is lifted to clear the guideway. A knurled knob is provided for the cam pin to facilitate turning it. The labels come on to the lateral guideway from the spool which is positioned to the rear of the way. The spool is housed in a circular casing 97 which is fastened to the base of the machine beneath the printing head arm. The spool 12 is loosely journalled on an axial shaft 98. The axial shaft also supports a removable circular dust plate; the plate slipping on the end of the shaft. A spring urged tension arm (not shown) is provided, under which the strip of labels passes, to take up the slack in the strip caused by the reciprocating action of the feed mechanism.

The label guideway is adapted to feed three different widths of labels. The guideway comprises a guide plate 99 and a pressure plate 100. The guide plate 99 extends rearwardly beyond the guideway table. The smallest width strip is threaded into the guideway beneath the guide plate forwardly to a point near the front end thereof, and is threaded up through a slot 101 to a position above the forward end of the guide plate to be engaged by the feed finger. The slot 101 is struck from the guide plate to provide a ramp 102 for guiding the strip of labels up through the slot. A guide channel 103 is provided for this narrowest width strip beneath the guide plate. The two wider strips of labels are threaded through a slot 104 near the rear of the guide plate 99 and extend forwardly on top of the guide plate to a point where they are engaged by the label feed finger. Above the guide plate, two ways are provided for the two larger width strips of labels. The narrow way is defined by a pair of marginal plates 107-107 fixed to the side edges of the guide plate 99. The wider way is defined by a pair of marginal plates 108-108, narrower than the plates 107-107 and fixed in position just above them. The pressure plate 100 is as wide as the narrowest way and is adapted to fit between the marginal plates

107-107 defining the narrower way. The pressure plate is fixed to the bottom of a cross bar 109 which is held loosely in position by a bolt 110, on the one end, and a pin 111, engaged in a fork, at the other end. The two ends of the cross bar 109 lie on the tops of the marginal plates 108-108. The two fastening means, the bolt and the pin, hold the plate against longitudinal displacement but permit the plate to be raised slightly from the guideway in a floating action. However, the pressure plate is limited in its upper movement by one arm of a bell crank 112 which is pivotally journalled, as at 113, on the outer plate of the ways 108-108. The bell crank is pivotally journalled on a bolt threaded through the left marginal plates into the frame. The bolt extends upwardly beyond the top of the bell crank and a spring on the bolt above the bell crank, seated against the head of the bolt 20 provides a cushion for the bell crank. The end of the other arm is bent upwardly in the form of a thumb plate to facilitate movement of the bell crank. The pressure plate is urged downwardly by a leaf spring 115 fixed at its one end 25 to the under side of the label feed finger carrier 86. The spring extends forwardly to engage the front end of the pressure plate and exert a downward pressure thereon. The pressure plate is adapted to fit down in the way defined by the two marginal plates 107-107. Therefore, when the second width strips of labels are fed up through the slot 104 onto the guide plate, the pressure plate holds it down into the smaller width way. The rear ends of the marginal plates 30 107-107 are feathered so that the widest strips pass over the top of them and are guided by the marginal plates 108-108. When these widest strips are being used, the floating pressure plate is lifted by the strip, still maintaining sufficient pressure on the top of the strip to hold it in the way. The pressure plate is provided with a medial groove 116 which terminates at the forward end of the pressure plate in a slot 40 117. The terminus of the groove ends just rearwardly of the slot 101 through which the narrowest strip of tickets passes up onto the top of the guide plate. The label feed finger 93 contacts the feed notches in the strip of labels through the slot 117 in the forward end of the pressure plate.

It may be seen that the pressure plate holds the strips of labels down against the guide plate while the feed finger extends through the slot 117 in the forward end of the pressure plate and contacts the notches in the strip for advancing them.

The forward end of the guide plate 99 preferably is bifurcated to correspond with the longitudinal slot 117 in the pressure plate 100 so that the feed finger 93, when in a notch in the strip for advancing it, presses directly on the bottom of the guideway. In order to make the passage of the strips smooth, a thin metal plate 118 is provided for the guideway at this point so that the tip of the wedge at the end of the feed finger 93 can ride easily thereon. The labels are advanced onto the platen below the printing head and are then printed and dispensed in an unbroken strip from the front of the machine.

The printing head is provided with the usual removable type chase, indicated at 120. Referring to Figure 9, it may be seen that the printing arm is pivotally journalled on a cross pin 121 carried in bearing blocks 122 at the rear of the

machine. The bearings are secured to the base of the machine by bolts, or other appropriate means, toward the rear of the gummed label roll housing. The journal for the printing arm is split to straddle a printing head actuating arm 123 which is also journalled on the cross pin 121. The forward end of the actuating arm 123 carries a roller 124 extending at right angles therefrom for engagement with a cam track 125 in the left face of a cam disc 126. The cam disc is keyed to the driven shaft 18 and, as with the feed carriage cam 17, makes one cycle per revolution. Near the middle of the actuating bar 123, an arm 127 extends upwardly and then forwardly where it is connected to the printing head (Figure 4). Means is provided for adjusting the connection of the lever to the arm in order to adjust the portion of the head relative to the platen for the correct printing pressure. The cam track is configurated to impart the necessary motion to the printing arm for inking the type and printing the tickets or labels.

To facilitate the movement of the arm and prevent locking in the cam track, the arm is urged upwardly by a spring 131 which is fastened to the lower end of a bar 132 depending from the rear of the printing arm down through an opening in the base. The bar 132 has the function of a lever, having its fulcrum on a bushing 133 on the cross pin 121. The spring is attached at its forward end to a rib of the base. Therefore, the tension of the spring acting on the bar will tend to lift the arm.

The forward end of the printing arm is guided and supported in an arcuate slot 128 in an extension of the plate 32 which is bolted to the frame of the machine. The printing arm is sustained by a bolt 130 which extends from the right side of the arm through the slot 128. Washers on the bolt on both sides of the slot are provided to sustain the arm against lateral displacement.

The change over from ticket feed to label feed is simple. The operator, if tickets are being fed at the time, first, throws the knurled handle 58 on the cam pin 57 to lift the forward ticket feed 45

finger 45 and then lifts the rear ticket feed finger 46 by pressing down on an extension 135, provided in the back of the pivoted finger for this purpose. This clears the fingers so that the strip of tickets can be withdrawn from the longitudinal guideway. The cam pin 57 sustains the forward finger 45 in the elevated position so that it will not interfere with the label feed as pointed out above. The rear finger can be released to ride on the bottom of the guideway since it does not affect the label feed. When the ticket guideway is cleared and the forward feed finger raised, the labels can be threaded into the label feed guideway. The smallest labels are threaded beneath the guide plate 99 to the slot 101 and then up onto the guide plate for engagement with the lateral feed finger 93. The other two width strips are threaded through the slot 104 in the guide plate 99, through the appropriate way, as defined by the marginal guide plates 107-107 and 108-108, and then forward to the feed finger 93. Although the present inventor discloses only three widths of ways for the label, it is believed apparent that any number of ways of different width could be provided by slightly modifying the ones disclosed here.

Having described my invention, I claim:

A machine for marking price tags, comprising, a frame, a pair of guideways formed on said frame, said guideways disposed at right angles and intersecting, a platen disposed at the intersection, means for printing tickets on the platen, feeding units for the respective guideways, said feeding units including fingers adapted to engage feeding notches in strips of price marking tags, the finger of one of said feeding mechanisms adapted to travel across the platen for feeding the endmost ticket to a severing knife mounted in position at the outer edge of the platen and a device for raising said finger from operative position whereby its travel across the platen will not interfere with the feed of tickets at right angles across the platen.

THOMAS G. TURNER.
